DESIGN FOR A THERMOMETER

Albert L. Stemwedel, Chicago, Ill., assignor to
Fee and Stemwedel, Inc., Chicago, Ill.

Application December 7, 1934, Serial No. 54,325

Term of patent 7 years

To all whom it may concern:

Be it known that I, Albert L. Stemwedel, a citizen of the United States, residing at 219 West Chicago Avenue, in the city of Chicago, in the county of Cook, and State of Illinois, have invented a new, original, and ornamental Design for a Thermometer, of which the following is a specification, reference being had to the accompanying drawing, forming part thereof.

The figure is a perspective view of a thermometer showing my new design.

I claim:

The ornamental design for a thermometer as shown.

In witness whereof, I hereunto subscribe my name this third day of December, 1934.

ALBERT L. STEMWEDEL.
